UNITED STATES PATENT OFFICE.

BROWN E. BARNES, OF PORTLAND, OREGON, ASSIGNOR TO WILLAMETTE IRON & STEEL WORKS, OF PORTLAND, OREGON, A CORPORATION OF OREGON.

PULLEY BLOCK.

Application filed June 8, 1922. Serial No. 566,862.

To all whom it may concern:

Be it known that I, BROWN E. BARNES, a citizen of the United States, residing at Portland, in the county of Multnomah and State of Oregon, have invented new and useful Improvements in Pulley Blocks, of which the following is a specification.

This invention is designed to provide a closure for the end of a pulley block. Pulley blocks, as ordinarily constructed, especially the heavy type of pulley blocks used with logging engines have the cheek pieces secured to each other at the end opposite the shackle but the securing means does not form a closure between the ends of the cheek pieces with the result that as the blocks are pulled along the ground as they often are these projecting cheeks tend to cut into the ground and to pick up earth, stones, and sticks, thus tending to block the sheave and throwing the stones and sticks in a manner dangerous, or disagreeable at least to the workmen in the neighborhood. The invention is further designed to strengthen the connection between the cheeks.

The invention is illustrated in the accompanying drawings as follows:—

Fig. 1 shows a central vertical section through a block.

Fig. 2 a side elevation, a part being broken away to better show construction.

Fig. 3 an elevation from the side of Fig. 2 of the end of the pulley block.

1 marks the sheave, 2 the hub of the sheave, 3 the bearing bushing in the sheave, 4 a bearing pin, 5 a tie rod for securing the bearing pin in place, 6 locking pieces for securing the pin 4 in the cheek 7, and 8 a connecting shackle for the cheeks forming a holding means. These parts may be of ordinary construction.

The closure piece 10 is made up of the spacing blocks 11 which have perforations 12 through which the bolts 9 extend clamping the cheeks on the closure piece. The spacing blocks 11 are connected by an intervening plate which is strengthened by an inwardly extending web 13. The ends 14 extend inwardly from the blocks 11, these ends extending into the groove of the sheave and being preferably shaped to conform to the sheave groove so as to make an efficient clo-

sure against the carrying in of any material between the sheave and spacing blocks 11.

The closure blocks, it will be seen, give an end to the pulley block that tends to carry it out of the ground when it is pulled forward rather than giving it a tendency to dig in as where the closure plate is absent and the plate particularly in connection with the ends makes a closure preventing the wedging in of stones, sticks, or other obstructions between the sheave and bolts securing the cheeks.

What I claim as new is:—

1. In a pulley block, the combination of a sheave; cheek pieces between which the sheave is journaled; a holding member at one end of the cheek pieces; and a closure member at the opposite end of the cheek pieces formed with spaced blocks and a connecting plate, said connecting plate having an inwardly extending web.

2. In a pulley block, the combination of a sheave; cheek pieces between which the sheave is journaled; a holding member at one end of the cheek pieces; and a closure member at the opposite end of the cheek pieces having ends extending into the sheave groove.

3. In a pulley block, the combination of a sheave; cheek pieces between which the sheave is journaled; a holding member at one end of the cheek pieces; and a closure member at the opposite end of the cheek pieces having ends extending into the sheave groove and conforming to the shape of the groove.

4. In a pulley block, the combination of a sheave; cheek pieces between which the sheave is journaled; a holding member at one end of the cheek pieces; and a closure member at the opposite end of the cheek pieces formed with spaced blocks and a connecting plate, the connecting plate having an inwardly extending web, the closure member having ends extending into the groove of the sheave and having a web in continuation of the web back of the connecting plate.

In testimony whereof I have hereunto set my hand.

BROWN E. BARNES.
